PAY STATEMENT AND ENVELOPE
ASSEMBLY

Wimer G. Overly, Oakmont, Pa., assignor, by
mesne assignments, to Pittsburgh Lithograph
Press Corporation, New York, N. Y., a corpora-
tion of New York

Application June 30, 1943, Serial No. 492,844

2 Claims. (CL 229—69)

1

The present invention relates to record papers, and more particularly to pay statement and envelope assembly.

The pay statement of the present invention comprises an envelope adapted to contain wages and a statement blank secured to said envelope and adapted to be filled with entries or details having reference to the wages contained in the attached envelope.

One object of the present invention is to provide a combined envelope and statement blank which can be easily inexpensively manufactured, and which can be easily handled, as for example for typing operations in a typewriting machine.

Another object is to provide an envelope and statement blank assembly which is constructed and outlined to guide typing along those sections free from overlapping sheet edges which might cause any typing overlying said edges to be shaded or be otherwise rendered imperfect.

The present invention provides for a strip which comprises the combination of a continuous sheet subdivided into successive statement blanks by transverse weakened tear lines, and a file of open side seam envelopes secured to respective blanks, and which is folded into a zig-zag pack for easy handling.

Another object is to provide a composite strip of the general character above referred to constructed to permit zig-zag folding of said strip with no tendency to fanwise expansion of the resulting pack.

Another object is to provide a manifold strip with blank and envelope units adhesively secured together along parallel oblong areas between the transverse tear lines, and with vent openings preventing the formation between the unattached sections of said units of air pockets which may prevent close packing or adversely affect typing of the strip.

Various other objects, features and advantages of the invention will be apparent from the following particular description, and from an inspection of the accompanying drawings, in which

Fig. 1 is a top plan view of a portion of a composite manifold strip embodying the present invention, but shown without the form printing;

Fig. 2 is a top plan view of the left hand end of an envelope statement unit which embodies the present invention, and which is shown filled in with entries and details respecting the wages contained in the attached envelope;

Fig. 3 is a top plan view of the right hand end of the envelope statement unit, which has the duplicate slip and which slip is shown filled in

2

with entries and details respecting the wages contained in the corresponding envelope;

Fig. 4 is a bottom view of a portion of a composite manifold strip embodying the present invention, and shown with an envelope folded back to reveal the gummed areas;

Fig. 5 shows a side elevation of a composite strip of the present invention folded along each successive transverse tear line into a zig-zag pack; and

Fig. 6 shows a side elevation of a composite strip of the present invention folded along every other tear line, so that each fold leaf comprises two envelope units.

Referring to the drawings, the manifold strip of the present invention comprises a continuous record or statement sheet 11 which is divided into successive statement blanks 12 by a series of transverse weakened tear lines 13 shown formed by a series of spaced perforations, as will be more fully described, and which has a series of equally spaced feed registering apertures 14 along opposite sides thereof. These apertures 14 serve to receive the impaling pins from a feed roller during assembly to feed the continuous record sheet towards junction with the file of advancing envelopes at predetermined registering speed with respect to said envelopes, and may also serve in a similar manner to feed the assembly manifold strip through a typewriter when filling out the statement blanks 12.

Each of the statement blanks 12 is divided into an original form slip 15 and a smaller duplicate form slip 16 by means of a weakened tear line 17, shown as a perforated line extending longitudinally along the record sheet 11 and intersecting the transverse tear lines 13 at right angles thereto. The outer exposed face of the original slip 15 has a series of printed box and column lines 20, which serve to define the location of the statements to be entered on said slips, and the duplicate slips 16 may have similar markings 21 serving the same purpose. Such legends as "Employee's name," "Hrs. worked," "Gross pay," "Net pay," and other pertinent notations may be printed on the slips 15 and 16 as shown in Figs. 2 and 3.

Attached to each original slip 15 is an open side seam envelope 22 having its front panel 23, Fig. 4, adhesively secured to the inner blank face of the statement slip 15 along parallel rectangular transversely spaced elongated areas 24, and having its seal flap 25 extending transversely of the sheet 11. The envelope 22 is desirably of the so-called flat type formed from a single sheet

of paper, and folded transversely to define the front panel 23, the rear panel 26 and the flap 25, and folded along the front panel sides to form inward tabs or side flaps 27 gummed to the side edges of the rear panel or bottom flap 26.

The envelope 22 is smaller than the corresponding statement slip 15, and is confined within the rectangular boundaries thereof to permit these slips 15 with attached envelopes to be readily separated along the tear lines 13, to permit easy separation of the duplicate slips 16 along the tear lines 17, and to allow easy zig-zag folding of the manifold strip along the transverse tear lines 13.

The longitudinal edges of the envelopes 22 are spaced a short distance from the tear lines 13, and the gummed areas 24 may be spaced a short distance inwardly from these envelope edges or they may extend to said edges so that the transverse sections of the composite strip extending along the tear lines 13 and between adjoining envelopes are of single ply, and easily foldable along said tear lines.

The composite strip is folded alternately along its tear lines 13 in opposite directions in the form of a zig-zag pack. In Fig. 5 this pack is shown slightly expanded and formed with the composite strip folded along each successive tear line 13, so that each leaf contains a single statement blank 12 and an attached envelope. This folding of the composite strip along each tear line has the advantage of rendering all of these lines of uniform tearing strength.

As far as certain aspects of the invention are concerned, the composite strip of the present invention can be folded along tear lines 13 in any ordinal sequence desired. For example, in Fig. 6 is shown a slightly expanded zig-zag pack in which the composite strip is folded along every other tear line 13, so that every leaf contains more than one blank 12, two statement blanks with two attached respective envelopes being shown.

It should be noted from Figs. 5 and 6 that by positioning the envelopes with their flaps extending transversely of the strip, these flaps will extend alternately on opposite sides of the zig-zag pack, so that the number of plies on opposite sides of the pack are about the same. The pack will thereby lay flat and will not tend to extend fan-wise as in the case of a pack containing unequal numbers of plies on opposite sides.

The ungummed sections 28 of the composite strip separating the ungummed sections 24 form pockets, and unless the air from these pockets is permitted to escape freely, close zig-zag packing of the strip will be difficult and typing on the strip will be defective. The ordinary tear lines consisting of a series of short slits, are effective to weaken the lines for tearing, but would be too small and too confining to permit free escape of air therethrough. To permit the free escape of air from the pockets 28, the tear lines 13 in accordance with the present invention consist of a series of the usual short tear perforations 29 opposite the ends of the gummed areas 24, and longer air vent slits 30 opposite the ends of said pockets. These slits 30 are desirably long enough to extend across the full width of the

pockets 28 between the gummed areas 24. Air accumulating in the pockets 28 will vent freely through the slits 30, so that the different unglued plies for each unit of the composite strip will lie close together in a pack and enable the web to lie close to the platen of the typewriter.

In the use of the composite strip described, the strip is fed from a zig-zag pack of the type shown in Figs. 5 and 6 around the platen of a typewriter by means of suitable pins on the platen, said pins engaging in registering apertures 14, and the original and duplicate statement slips 15 and 16 are filled in with the required entries pertaining to the wages to be enclosed in the attached envelope as shown in Figs. 2 and 3.

It should be noted that the box and column markings 20 in the original statement slip 15 and the printed legends thereon are arranged to guide typing on those areas of the strip which do not overlap overlapping sheet edges as shown in Figs. 2 and 3. For example, the box outline 35 has its ends spaced inwardly from the edges of the envelope tabs 27, and the column lines 36 have their upper ends spaced below the outer edge of the seal flap 25 in closed position of said flap. These markings 35 and 36 with the corresponding printed legends serve as a guide for the typist, so that no typing is done on the sheet overlying overlapping sheet edges, thereby maintaining the typing on the sheet uniform.

After typing of the statement slips 15 and 16 above referred, the composite strip can be severed along the tear lines 13 into individual units, and the envelopes 22 filled. The employee receives the wage envelope 22 with attached statement slip 15, while the duplicate slip 16 is retained by the employer.

I have described what I believe to be the best embodiments of my invention. I do not wish, however, to be confined to the embodiments shown but what I desire to cover by Letters Patent is set forth in the appended claims.

I claim:

1. A composite strip comprising a continuous sheet subdivided into successive statement blanks by a series of transverse tear lines, and envelopes gummed to said blanks respectively along parallel areas extending between successive tear lines with the flaps of said envelopes extending on the outside of said sheet, said tear lines being formed with slits opposite the ends of the ungummed areas extending across the full width of said ungummed areas to form vent openings for the pockets defined by said latter areas.

2. A composite strip comprising a continuous sheet subdivided into successive statement blanks by a series of transverse tear lines, and envelopes gummed to said blanks respectively along parallel areas extending between successive tear lines with the flaps of said envelopes extending on the outside of said sheet, said tear lines being formed with a series of short perforations opposite the ends of the gummed areas and formed with substantially longer perforations opposite the ends of the ungummed areas to form vent openings for the pockets defined by said ungummed areas.
